UNITED STATES PATENT OFFICE.

THADDEUS S. GRIMES, OF ATLANTA, GEORGIA, ASSIGNOR TO EDWARD VAN WINKLE, OF ATLANTA, GEORGIA.

PNEUMATIC COTTON-ELEVATOR.

No. 823,858.

Specification of Letters Patent.

Patented June 19, 1906.

Application filed September 30, 1905. Serial No. 280,837.

To all whom it may concern:

Be it known that I, THADDEUS S. GRIMES, a citizen of the United States, residing at Atlanta, county of Fulton, in the State of Georgia, have invented certain new and useful Improvements in Pneumatic Cotton-Elevators; and I do hereby declare the following to be a full, clear, and exact description of the invention, such as will enable others skilled in the art to which it appertains to make and use the same.

My invention relates to cut-off valves for pneumatic cotton-elevators; and the object of my invention is to provide a cut-off valve which will automatically allow the cotton to be delivered to the gin or other device at stated intervals and which will at the same time not interrupt or interfere with the current of air drawn in by the suction-fan.

With this object in view my invention consists in the construction and combinations of parts, as hereinafter described and claimed.

In the accompanying drawings, Figure 1 is a side view of my improved device, the valve being shown in dotted lines; and Fig. 2 is a side view of the same, taken at right angles to Fig. 1.

a represents a driving-pulley mounted on a shaft *b*, which is secured in bearings *c c* on a plate *d*, which is fastened to the side *s* of a suction-pipe which is of the ordinary type and delivers to a gin or other machine. This suction-pipe is preferably square and made of wood. To the shaft *b* is fastened a worm *e*, which meshes with a worm-wheel *f*, which is mounted on the stud-shaft *g*, supported in the frame *d*. This worm-wheel is of a spider-frame construction and on one of its arms is provided with a roller *h*.

i represents the cam for operating the valve, which is mounted on the shaft *l* and is provided with a handle *j* and a counterweight *k*. By means of the handle the valve which is mounted on the shaft *l* can be operated by hand whenever desired. The cam *i* is provided with an actuating-surface *m*, an idle surface *n*, and an actuating-surface *o*. As the wheel *f* revolves the roller *h* comes in contact with the curved portion *m* of the cam, moving the latter (and the valve operated thereby) to the position shown in dotted lines in Fig. 1. The valve remains in this position for a short time while the roller *h* is passing

under the portion *n* of the cam, and the roller then strikes the portion *o* of the cam and turns back the valve into its original position.

The valve itself consists of two pairs of radial arms *p*, fastened to the shaft *l*, and to each pair of these arms is fastened a curved quadrant *q*. Over these quadrants is stretched sheet metal, thus making the valve a section of a cylinder. The side of the suction-pipe *s* is provided with curved extensions *r*, inside of which is the valve. The opening between the extensions *r* is of approximately the same area as the opening through the suction-pipe *s*, the result being that as the valve is opened or closed substantially the same area will be left for the passage of air to the suction-fan.

The operation is as follows: The pulley *a* is revolved by any suitable means in the direction of the arrow 9, which causes the revolution of the gear-wheel *f* in the direction of the arrow 8. In the position shown in Fig. 1 the roller *h* strikes the cam *i* and turns the valve to the left. The valve remains in this shifted position for a short time and is then turned backward to its original position as the roller *h* strikes the part *o* of the cam. In the position shown in full lines the air passes through the pipe *s*, as indicated by the arrows 6. In the position shown in dotted lines the air passes into said pipes, as indicated by the arrows 7, and no matter what the position of the valve is an opening or openings of constant area are left for the air, so that the action of the suction-fan which draws the air through the pipe *s* is not interfered with in any way. This is a very important feature of my invention.

It should be noted that the opening and closing of the valve occupies only a small interval of time as compared with the time required for a complete revolution of the wheel *f*. This is in order that the valve may be automatically opened, kept open for a short time, and then closed at considerable intervals.

While I have shown a worm wheel and gear for operating the valve, I wish it to be distinctly understood that I do not limit myself to this means, as any usual mechanical means for operating the valve might be employed.

Having thus described my invention, what

I claim as new, and desire to secure by Letters Patent, is—

1. The combination of a suction-pipe provided with an opening in its side of substantially the same area as the pipe itself, a valve adapted to normally close said opening, and means for opening and closing said valve at intervals, substantially as described. 30
2. The combination of a suction-pipe provided with an opening in its side of substantially the same area as the pipe itself, a quadrant-valve centrally mounted in said pipe, and means for automatically operating said valve at intervals, consisting of a cam, a gear-wheel provided with a roller, and means for operating said gear-wheel, substantially as described. 35
3. The combination of a suction-pipe provided with an opening in its side of substantially the same area as the pipe itself, a quadrant-valve mounted on a shaft located in the center of the pipe and provided with a handle and counterweight, and means for automatically operating said valve, substantially as described. 40
4. The combination of a suction-pipe pro- 45

vided with an opening in its side of substantially the same area as the pipe itself, a shaft centrally mounted in said pipe, a quadrant-valve mounted on said shaft, a handle, counterweight and cam also mounted on said shaft, a wheel carrying a roller adapted to engage with said cam, and means for operating said wheel, substantially as described.

5. The combination of a suction-pipe provided with an opening in its side of substantially the same area as the pipe itself, and also provided with curved extensions, a shaft centrally mounted in said pipe, a quadrant-valve mounted on said shaft, an operating handle, counterweight and cam also mounted on said shaft, a gear-wheel provided with a roller adapted to engage said cam, and a worm for operating said gear-wheel, substantially as described.

In testimony whereof I affix my signature in presence of two witnesses.

THADDEUS S. GRIMES.
